UNITED STATES PATENT OFFICE.

PERCY L. COZZENS, OF NEW YORK, N. Y.

MANIFOLDING SALES-BOOK.

SPECIFICATION forming part of Letters Patent No. 767,927, dated August 16, 1904.

Application filed June 4, 1903. Serial No. 160,078. (No model.)

To all whom it may concern:

Be it known that I, PERCY L. COZZENS, a citizen of the United States, residing at New York, (Brooklyn,) in the county of Kings and State of New York, have invented certain new and useful Improvements in Manifolding Sales-Books; and I do hereby declare the following to be a full, clear, and exact description of the invention, such as will enable others skilled in the art to which it appertains to make and use the same.

This invention relates to that class of memorandum sales-books in which the memorandum consisting of particulars of the sale, the address of the purchaser, &c., are written on one leaf and transferred to a duplicate leaf by means of an interposed sheet of transfer-paper.

Heretofore it has not been possible to obtain in duplicate memorandum sales-books more than an original and a duplicate copy of the address of a purchaser, whereas it is important and, indeed, quite necessary in most cases that a greater number of copies of the address should be produced for checking off and recording in the various departments of large establishments.

The object of my invention is to provide a duplicate memorandum sales-book in which four copies of the address of a purchaser may be procured at one writing.

The invention will be described in connection with the accompanying drawings and afterward particularly pointed out in the claims.

In the accompanying drawings, Figure 1 represents a perspective view of a memorandum sales-book made up of continuous or connected leaves used in certain forms of memorandum-books and showing the invention applied to this style of book; Fig. 2, a similar view, on an enlarged scale, of a number of continuous leaves detached and showing clearly the position of the additional address-slips and the arrangement of the transfer-sheets for producing quadruplicate copies of the address; Fig. 3, a perspective view of detached original and duplicate leaves in another form of memorandum sales-books and with the additional address-slips connected with the original and duplicate leaves. Fig. 4 is a longitudinal section of said detached leaves with

the transfer-sheets in position for producing duplicate copies of memoranda of a sale and quadruplicate copies of the address of the purchaser.

Referring to the drawings, A B are the stiff covers of a book which are connected together by a flexible back C, so that the covers can be opened and closed in the usual manner.

D is an original leaf, and E a duplicate leaf, both of which are ruled with lines for writing and columns for figures and also have printed on them date-lines, numbers, and squares for various entries with printed headings for each, the name of the firm, &c. Both original and duplicate leaves are divided transversely into two parts--viz., the sales-slips *a a'*, on which memoranda relating to the sale are written, and address-slips *b b'*, on which the address of the purchaser is entered. Between the original and duplicate sales-slips *a a'* and the original and duplicate address-slips *b b'* there are perforated lines *d d'* to facilitate tearing apart the sales and address slips after the entries are made and the leaves detached from the book.

The improvements that form the subject of this application are represented in Figs. 1 and 2 applied to a book having the leaves formed in a continuous strip, with perforated lines between, on which they are folded back and forth or in zigzag fashion. In this style of book the printing is done on opposite sides of the original and duplicate leaves, so that when the original is folded over on top of the duplicate the printed and ruled sides of both will be uppermost and the printed matter, ruled lines, columns, date-lines, &c., will register properly. Between the bottom edges of the original and duplicate leaves there is a section of paper equal, say, to twice the length of the address-slips. This section is folded inward on a middle perforated line *e*, and thus forms a bellows fold F at the bottom of the book. By this means a triplicate slip *f* and quadruplicate *g* are formed, and these are printed and ruled to correspond to the address-slips on the original and duplicate leaves, and perforated lines *e'* are made between the triplicate and quadruplicate slips *f g* and the original and duplicate slips *b b'*,

respectively, to facilitate tearing the slips apart. Like the original and duplicate leaves the printing on the triplicate and quadruplicate address-slips is on opposite sides—that is, the printed matter on the triplicate *f* is on the side opposite to that of the original address-slip *b* and the printed matter on the quadruplicate *g* is on the same side as the original or opposite to that on the duplicate *b'*. Hence when the triplicate and quadruplicate are folded between the address-slips *b b'* the printed surfaces of both are uppermost, as may be seen by the lower set of detached leaves in Fig. 2. The book composed of these continuous leaves is placed on one side of the cover, where it is held at both ends under the spring-clamps *l m*, which permit the folded ends of the original and duplicate leaves to be drawn out and torn off readily, when they are to be detached after a memorandum has been made. A sheet of single carbon-paper *G* is attached to the book by the carbon-sheet holder *n*, connected with the clamp *l*. This sheet lies on top of the duplicate leaf *E* and extends to the bottom, its lower part thus lying between the duplicate address-slip *b'* and the quadruplicate address-slip *g*, while above the address-slips it is between the original and duplicate sales-slips. A short sheet of double carbon-paper *H* is attached to a carbon-holder *o* on the bottom clamp *m* and lies between the address triplicate and quadruplicate slips *f g*. By the arrangement of the original and duplicate sales-slips and the original, duplicate, triplicate, and quadruplicate address-slips and the sheets of single and double carbon-paper above described when a memorandum is made on the original sales-slip *a* it is transferred by the carbon-sheet *G* to the duplicate sales-slip *a'*, and when the address of the person to whom the sale was made is written on the original address-slip *b* it is transferred by the carbon-sheet *G* to the duplicate address-slip *b'* and by the double carbon-paper *H* to the under side of the triplicate address-slip *f* and to the upper side of the quadruplicate address-slip *g*. The paper of which the leaves of the book are made is transparent, so that writing can be easily read through it. Hence as the address is transferred to the under side of the triplicate address-slip *f* it is plainly visible and can be read through the paper with perfect ease. After the sales-memoranda and address have been written the duplicate leaf *E* is torn off from the succeeding original leaf *D* at the folded and perforated line *h* at the top, and then the original and duplicate address-slips are separated from the original and duplicate sales-slips and finally separated from each other, one of the address-slips being sent to the packing-room, another is sent for record in the delivery department, and the other two are disposed of in the usual manner.

Figs. 3 and 4 show the improvements applied to a memorandum sales-book, in which each set *I* of original and duplicate leaves *D E* is separate from the others and are bound together at the top by means of a stub *J* at the head of the duplicate leaf. As in the case of the continuous book, a section of paper is interposed between the original and duplicate leaves, which are each divided into sales-slips *a a'* and address-slips *b b'*, the same as the continuous leaves, and this section is divided to form triplicate and quadruplicate address-slips *f g* and turned inward to form the bellows fold *F*. The single carbon-leaf *G* is bound to the stub at the top of the book by its upper end, and the short double carbon-sheet *H* is bound by its lower end to a suitable holder at the bottom of the book and its free portion lies between the triplicate and quadruplicate address-slips *f g*.
I claim—

1. A manifolding sales-book consisting of a number of sets each comprising a pair of original and duplicate leaves each leaf divided by a weakened line into two slips, and a corresponding number of sections one of which is interposed between corresponding slips of each pair of original and duplicate leaves each of these sections being composed of two slips divided from each other by weakened lines said slips being coterminous with the said corresponding slips of the original and duplicate leaves, substantially as specified.

2. A manifolding sales-book consisting of a number of sets each comprising a pair of original and duplicate leaves each leaf divided by a weakened line into two slips, and a plurality of slips interposed between corresponding slips of each pair of original and duplicate leaves said plural slips being coterminous with the said corresponding slips of the original and duplicate leaves, substantially as specified.

3. A manifolding sales-book consisting of a strip of paper folded zigzag to form a number of sets of leaves and a corresponding number of sections one of which is interposed between the leaves of each set each set of leaves comprising a pair of original and duplicate leaves each leaf divided by a weakened line into two slips and each of the sections being composed of two slips divided from each other and from the original and duplicate leaves by weakened lines said slips being coterminous with the corresponding slips of the original and duplicate leaves, substantially as specified.

4. A manifolding sales-book consisting of a number of sets each comprising a pair of original and duplicate leaves each leaf divided by a weakened line into two slips, and a corresponding number of sections one of which is interposed between corresponding slips of each pair of original and duplicate leaves each of these sections being composed of two slips divided from each other by weakened lines said slips being coterminous with the

said corresponding slips of the original and duplicate leaves, in combination with a single transfer-sheet lying on top of a duplicate leaf and between the undermost slip of the interposed section and the corresponding slip of the duplicate leaf, and a short double transfer-sheet inserted between the slips of the interposed section, substantially as specified.

5. A manifolding sales-book consisting of a number of sets each comprising a pair of original and duplicate leaves each leaf divided by a weakened line into two slips and a plurality of slips interposed between the corresponding slips of each pair of original and 10 duplicate leaves said plural slips being coterminous with the said corresponding slips of the original and duplicate leaves, in combination with a single transfer-sheet lying on top of a duplicate leaf and between the undermost interposed slip and the corresponding slip of the duplicate leaf, and a short double transfer-sheet inserted between the interposed 15 slips, substantially as specified.

6. A manifolding sales-book consisting of a strip of paper folded zigzag to form a number of sets of leaves and a corresponding number of sections one of which is interposed between the leaves of each set each set of leaves comprising a pair of original and duplicate leaves each leaf divided by a weakened 20 line into two slips, and each of the sections being composed of two slips divided from 25

each other by weakened lines said slips being coterminous with the corresponding slips of the original and duplicate leaves, in combination with a single transfer-sheet lying on top of a duplicate leaf and between the lowermost slip of the interposed section and the corresponding slip of the duplicate leaf, and a short double transfer-sheet inserted between the slips of the interposed section, substantially 30 as specified.

7. In memorandum sales-books the combination of original and duplicate leaves having address-slips thereon, and a section of paper interposed between the original and duplicate leaves divided into two parts by a perforated folding-line said section being folded inward between the original and duplicate address-slips, a single transfer-sheet fastened at one end and lying on top of the duplicate leaf and under the lowermost of the additional address-slips, and a double transfer-sheet fastened at one end and projecting between the infolded additional address-slips, substantially 40 as specified.

In testimony that I claim the invention above set forth I affix my signature in presence of two witnesses.

PERCY L. COZZENS.
